DOOR OPERATING MECHANISM

Edward R. Greer, Springfield, Ill., assignor to
 Allis-Chalmers Manufacturing Company, Milwaukee, Wis., a corporation of Delaware

Application June 20, 1936, Serial No. 86,276

9 Claims. (Cl. 298—35)

The invention relates to dump wagons and is concerned more specifically with a mechanism for operating the doors of such vehicles, particularly bottom dump doors. Subject matter disclosed but not specifically claimed herein is claimed in United States Patent 2,092,309, September 7, 1937, to E. R. Greer and E. F. Norelius, Door operating mechanism.

In the operation of a bottom dump wagon it is usually desired that the doors, upon unlocking, open freely, that is, practically without restraint, so that the entire load may dump practically all at once and the doors may strike a stop at the end of their opening movement rather violently in order to jar loose any dirt which may cling to the doors. On the other hand, it has become a preferred practice to close the doors of a dump wagon by mechanical power after the load has been dumped, and in order to answer both of the mentioned requirements, that is, the requirement of unrestrained opening movement of the doors and the requirement of closing the doors by mechanical power, the following mode of operation has heretofore been suggested. A reciprocable element such as a piston, is suitably connected with a door actuating shaft to impart door closing movement to the shaft by movement of the piston in one direction. After the doors have been closed they are held closed by means other than the piston and the latter is returned to its starting position independently of opening movement of the doors. The return movement of the piston to its starting position while the doors are being held in closed position relieves the doors from the work of restoring the piston to its starting position, and the doors may therefore open substantially without restraint.

It is an object of the invention to provide an improved mechanism of the above mentioned character.

Another object of the invention is to provide a hydraulically actuated door operating mechanism which permits unrestrained opening of the doors in the mentioned manner, which is simple and compact in construction, and efficient in operation.

These and other objects and advantages of the invention will be apparent from the following description. A clear conception of an embodiment of the invention and of the operation of a device constructed in accordance therewith, may be had by referring to the drawings accompanying and forming a part of this specification in which like reference characters designate the same or similar parts in the various views:

Fig. 1 is a side view of a cart type bottom dump wagon hitched to a tractor;

Fig. 2 is a detail view of a winding shaft for closing the doors of the bottom dump wagon shown in Fig. 1;

Fig. 3 is a rear view of the door winding mechanism at the rear of the bottom dump wagon shown in Fig. 1;

Fig. 4 is a side view of the mechanism shown in Fig. 3;

Fig. 5 is a section on line V—V of Fig. 3, showing the mechanism in a position different from the position in which it is shown in Fig. 4;

Fig. 6 is a section on line VI—VI of Fig. 3, showing the mechanism in the same position in which it is shown in Fig. 5;

Fig. 7 is a diagrammatic view of a hydraulic power system in connection with the winding mechanism shown in Fig. 3; and

Fig. 8 is a partial section on line VIII—VIII of Fig. 1.

The bottom dump wagon shown in Fig. 1 has a substantially rectangular tubular frame 7, on which a hopperlike wagon box 9 is mounted, the rear wall of the wagon box being indicated by 10. A pair of bottom dump doors 1 are hingedly secured to the longitudinal side portions of the frame 7 by means of suitable hangers generally indicated in Fig. 1 by the reference character 8 and more clearly shown in Fig. 8, Fig. 8 being a section through the lower near side of the wagon, shown in Fig. 1. As shown in Fig. 8, a U-bolt 86 is secured to a plate 87 extending downwardly from the tubular member 88 of the frame 7, and a casting 89 secured to the door 1 has a pair of ears 90 at opposite sides of the U-bolt 86. A pin 91 extending through the ears 90 and through the U-bolt 86 pivotally connects the casting with the U-bolt and therefore the door 1 with the frame 7. The casting 89 is also formed with a socket in which a coil spring 92 is seated, the coil spring being wound of square wire and adapted to be compressed between the tubular frame member 88 and the bottom of the socket in the casting. Each door 1 is hingedly connected to the frame 7 by three hanger arrangements of the type shown in Fig. 8, and it will be seen that if the doors are permitted to swing open without restraint the coil spring 92 will come into contact with the tubular frame member 88 but as the springs are comparatively weak, they will become solid almost instantly and the doors will be stopped in their opening movement very suddenly, producing a jar upon the doors which will shake loose any dirt that may cling to the doors.

The wagon is hitched to a tractor 4, of which only the rear end is shown in Fig. 1, a driver's seat on the tractor being indicated by the reference character 5. The tractor and the wagon are flexibly connected by a universal hitch 6, so that the tractor and the wagon may move relative to each other when the vehicle train is driven through a curve or over rough ground. A winding shaft 11 is mounted on the wagon box 9 by means of journal bearings 12 and 13 (Fig. 2) 60

- which are secured to the outer side of the rear wall 10 of the wagon box. The doors 1 are connected with the winding shaft 11 through a chain arrangement comprising chain portions 2 secured 5 to the doors and guided over pulleys 3 mounted in the side walls of the wagon box, and chain portions 14 which are connected to the chain portions 2 and secured to sheaves 15 and 16 mounted on the ends of the winding shaft, as shown in Fig. 2. It will be seen that rotation of the winding shaft in clockwise direction, with reference to Fig. 1, will wind up the chain portions 14 on the sheaves 15 and 16 and thereby cause the doors to be closed, and that opening movement of the doors 15 will cause rotation of the shaft 11 in anti-clockwise direction, with reference to Fig. 1. The mechanism described hereinbelow serves the purpose of winding up the doors by rotation of the shaft 11 in clockwise direction, and on the other hand permits practically unrestrained rotation of shaft 11 in anti-clockwise direction during the opening movement of the doors, so that a load may be dumped from the wagon box all at once and any dirt clinging to the doors will be shaken loose by jar of the doors when they come to a stop at the end of the opening movement.
- Mounted on the shaft 11 by means of bearings 56 is a frame 17, comprising side plates 18 and 19, an angle iron 20 connecting the side plates at their lower ends, and an angle iron 21 connecting the side plates between their upper and lower ends. The bearings 56 are secured to the side plates 18 and 19, and the frame 17 is prevented from swinging about the shaft 11 by a lug 22 which extends laterally from the side plate 19 and is bolted to the wagon box. Mounted on the frame 17 is a hydraulic cylinder 23 which is secured at its lower end to the angle iron 20 in the middle between the side plates 18 and 19. A piston rod 24 extends through the upper end of the hydraulic cylinder and is connected at its lower end to a piston 23' within the cylinder 23. The upper end of the piston rod 24 is connected to a cross head 25 which is guided between the side plates 18 and 19 and between guides 26 and 26' secured to the inner sides of the side plates 18 and 19. A pair of coil springs 27 urge the cross head upwardly and normally hold it in its highest position, that is, in the position in which the piston in the cylinder 23 is at the upper end of its stroke, heads at the upper ends of rods 55 being relied upon as a stop, the rods being adjustably secured at their lower ends to the angle iron 20 and having sliding engagement with the cross head 25. The coil springs are held in place by telescoping tubes 28 and 29, the tubes 28 being secured to the angle iron 20 and the tubes 29 to the cross head 25. A link chain 30 connects the cross head 25 with the winding shaft 11, one end of the link chain being secured to the cross head as shown in Fig. 4, and the other end of the chain being secured to a sleeve 31 with suitable fastening ears 32, the sleeve being rigidly secured to the shaft 11, see Fig. 2.
- The sheaves 15 and 16 on the winding shaft 11 have sufficiently large diameters so that rotation of the shaft 11 through an angle of about 250° in one direction will cause full opening of the doors, and so that rotation of the shaft 11 through the same angle in the opposite direction will cause complete closing of the doors from their fully open position. In Fig. 6 the sleeve 31 and the fastening ears 32 thereon are shown in the position which they occupy when the doors 15 are fully open; that is, in the position of the

sleeve 31 and ears 32, as shown in Fig. 6, the shaft 11 is in a rotated position in which the chains 14 are unwound from the sheaves 15 and 16 and from which position the shaft 11 must be rotated in anti-clockwise direction, with reference to Fig. 6, through an angle of about 250° in order to close the doors completely. Such rotation is imparted to the shaft 11 through the link chain 30 by a descent of the cross head 25 in the frame 17. In order to cause a downward movement of the cross head, fluid under pressure, preferably oil, is admitted into the cylinder 23 above the piston therein as at 33, and when the piston reaches the lower end of its stroke the sleeve 31 and fastening ears 32 thereon are in the position shown in Fig. 4, which is the position which the sleeve and ears occupy when the doors are completely closed. After the shaft has been rotated through an angle of about 250° in order to close the doors, reverse rotation thereof is prevented by a ratchet gear described more fully hereinbelow, the oil pressure above the piston in the cylinder is released and the cross head returns into its highest position under the pressure of the coil springs 27. Due to the upward movement of the crosshead, while the shaft 11 is prevented from rotating in door opening direction, the chain 30 slackens and, being subject to the force of gravity, it assumes the form of a loop the lower portion of which rests on a shelf 34 as shown in Fig. 4. The shelf is secured to the cross head 25 in any suitable manner. Instead of letting the slack chain rest on a shelf, as shown, a spring pressed roller may be employed to pull the slack chain away from the shaft 11 and from the cross head 25 into a position substantially as shown in Fig. 4, the purpose being to prevent the slack chain from becoming entangled in the mechanism.

The ratchet gear for holding the shaft 11 against reverse rotation after the doors have been closed, is shown at the right of Fig. 3. It comprises a ratchet wheel 35 which is keyed on the shaft 11, and a pawl 36 supported by a pair of arms 37. The arms 37 are rigidly secured to a long sleeve 38 which is rotatably supported on a pin 39, the pin being mounted at one end in an upward extension of the side plate 18 of the frame 17, and at the other end in a plate 40 pivotally supported on the shaft 11 and connected at its lower end to the side plate 19 of the frame 17 by a cross plate 41. The cross plate 41 carries an adjustable stop, in the form of a set screw 42, for the pawl supporting arms 37, the latter being connected at their lower ends by a cross piece 43 which engages the end of the set screw 42. A spring 44 connected at one end to the side plate 19 of the frame 17 and at the other end to one of the arms 37, draws the cross piece 43 against the set screw 42. The pawl 36 is pivotally mounted between the arms 37 on a pin 45 and has a depending weighted portion so as to be urged by gravity into engagement with the teeth of the ratchet wheel 35. The portions of the arms 37 between the pins 39 and 45, the pins and the pawl, constitute a toggle relationship which may be adjusted by the set screw 42.

The ratchet wheel is unlocked by swinging the arms 37 outwardly, that is, away from the set screw 42. For this purpose the sleeve 38 carries two bell crank levers 46 and 47 which are rigidly secured to the sleeve at opposite sides of a central vertical plane through the cylinder 23. Fig. 4 shows the bell crank lever 47 in the position which it occupies when the cross piece 43 of the

pawl supporting arms 37 engages the set screw 42, and in that position the upper arm of the bell crank lever extends substantially horizontally from the sleeve 38 and over the shaft 11, 5 while the lower arm extends downwardly and outwardly towards the wall of the wagon box on which the mechanism is mounted. The other bell crank lever 46 is similarly positioned on the sleeve 38, and the ends of the lower arms of both 10 bell crank levers are connected by an angle iron cross piece 48, one flange of the angle iron extending downwardly and rearwardly as shown in Fig. 6. The upper arms of the bell crank levers are connected at their ends by a pin 50 on which 15 two L-shaped trigger arms 49 are pivotally mounted by means of a sleeve 50', as more clearly shown in Fig. 3. The trigger arms 49 are connected at their lower ends by a cross member 51, and, near the angle of the L, by a plate like cross 20 member 57 which is not only a reinforcing element but primarily an abutment which may be struck by the lugs 32 and the chain 30 when the shaft 11 rotates in clockwise direction, with reference to Fig. 4, the purpose being to swing the 25 trigger arms 49 from the position in which they are shown in Fig. 4 into the position in which they are shown in Fig. 6. A cross pin 58 extending through the trigger arms 49 near their lower ends projects laterally therefrom and engages the guides 26' to limit swinging movement 30 of the trigger arms about the axis of pin 50 in clockwise direction, with reference to Fig. 4. When the cross pin 58 engages the guides 26' the cross member 51 of the trigger arms projects into 35 the path of the cross head 25, as shown in Fig. 4 and the upper legs of the trigger arms are kept spaced from the shaft 11 so that when the cross head 25 strikes the cross member 51, the trigger arms may move with the cross head in a downward direction at least for a limited length of 40 travel. Pivotally secured to another cross pin 59 between the trigger arms 49 is a bolt 53 which extends slidably through the downwardly and rearwardly extending flange of the cross member 45 48 between the bell crank levers 46 and 47, and which carries at its outer end a pair of nuts 60, one nut serving as a jam nut for the other. The nut 60 closest to the downwardly and rearwardly extending flange of the cross piece 48 is so adjusted 50 on the bolt 53 as to provide for some clearance between said nut and the flange, while the mechanism is in the position in which it is shown in Fig. 4. When the cross head 25 moves downward in what may be called an advance direction, it strikes the cross member 51 of the trigger arms and pulls downwardly on the trigger arms, causing the bell crank levers 46 and 47 to pivot on the axis of pin 39. The mentioned clearance between the first nut 60 and the cross piece 48 permits 55 limited pivotal movement of the bell crank levers while the cross member 51 remains engaged with the cross head 25. The limited pivotal movement of the bell crank levers about the axis of pin 39 is transmitted through the tube 38 to the pawl carrying arms 37, causing the pawl 36 to kick over center and consequent release of the ratchet wheel 35. Under the weight of the 60 doors 1 and the load resting thereon, if the wagon is loaded, the shaft will then spin around rapidly in clockwise direction, with reference to Fig. 4, and the lugs 32 will strike against the abutment 57, causing the cross member 51 to be pulled out of engagement with the cross head 25 and thus clearing the path of the latter for continued 65 downward movement. A tubular spacer 61 (Fig. 75

6) and a light compression coil spring 52 are arranged on the bolt 53 in the space between the downwardly and rearwardly extending flange of the cross piece 48 and the cross pin 59. When the cross member 57 on the trigger arms is struck 5 by the lugs 32 the ensuing movement of the trigger arms first compresses the coil spring 52 and then positively pushes the bell crank levers 46 and 47 about the axis of pin 39 in anti-clockwise direction with reference to Fig. 4, due to 10 contact of the tubular spacer 61 with the downwardly and rearwardly extending flange of the cross piece 48. The positive movement of the bell crank levers 46 and 47 by the tubular spacer 61 causes the pawl 36 to be moved still further away 15 from the ratchet wheel 35, as shown in Fig. 5. The cross member 57 rides on the chain 30 and the pawl will therefore remain in the position relative to the ratchet wheel 35 as shown in Fig. 5 until the shaft 11 is rotated in anti-clockwise 20 direction, with reference to Fig. 6, far enough to permit the trigger arms 49 to fall back into the position shown in Fig. 4, where the pin 58 engages the guides 26'; the pawl 36 will then again be in the position relative to the ratchet wheel 35, in 25 which it is shown in Fig. 4.

Referring to Fig. 7, a fluid reservoir is indicated by 62, the reservoir being mounted on the tractor as shown in Fig. 1. Mounted within the reservoir 62 is a pump 63 having a drive shaft 30 with a belt pulley 64 secured thereto at the outside of the reservoir. A belt 65 trained over the pulley 64 is driven by a constantly revolving shaft 66 on the tractor, as generally indicated in Fig. 1. The pump 63 has an intake opening 67 in communication with the interior of the reservoir 62, and a discharge opening 68 in communication with a conduit 69 leading out of the reservoir. The conduit 69 is connected through a hose 70 with the inlet opening 71 of a control valve generally indicated by 72. The valve has two outlet openings, an upper one 73 which communicates with the reservoir 62 through a conduit 74, and a lower one 75 which communicates with the cylinder 23 through a conduit 76. The body of the valve 72 is divided by a partition 77 into two compartments, a left one in communication with the inlet opening 71, and a right one in communication with the outlet opening 73. Communication between the right and the left compartment is controlled by a cylinder element 78 which is rotatable in the valve body and which communicates at its left open end with the left compartment of the valve body. Rotation of the cylinder 78 by means of the handle 79 brings an opening 80 of the cylinder into more or less registering relation with an opening 81 in the partition 77, and when the handle is rotated into one extreme position the opening 81 is fully open and when the handle is rotated into another extreme position the opening 81 is fully closed. An opening 82 in the partition 77 is normally closed by a spring pressed plunger 83, but upon excessive pressure in the left compartment the plunger 83 permits escape of fluid from the left to the right compartment through the opening 82. The left compartment communicates directly with the outlet opening 75 of the valve body, as shown in Fig. 7. A gate valve 85 is arranged in the conduit 76, and by closing the gate valve 85, the hydraulic cylinder 23 may be put out of commission, if desired.

The operation of the mechanism is as follows: Assuming that the mechanism is in the position shown in Fig. 4, the chains 14 are wound up on 75

the sheaves 15 and 16, and the doors are closed, as stated hereinbefore; the cross piece 43 of the pawl supporting arms 37 engages the set screw 42, and the pawl 36 engages the ratchet wheel 35, preventing the latter from turning under the torque which acts upon the shaft 11 through the chains 14, the chains being under tension due to the weight of the doors and due to the load of material thereon if the wagon box is loaded. The ratchet gear constitutes the only means for holding the doors closed, there being no other locks or latches for holding the doors closed. When the wagon arrives at the dump the operator, without stopping the vehicle, turns the handle 19 of the valve 72 into the extreme position in which the opening 81 is fully closed, and the entire fluid discharge of the pump 63 will then be forced into the cylinder 23 above the piston therein, as will be clear from Fig. 7. Under the fluid pressure acting upon the piston the cross head 25 begins to descend and strikes the cross member 51 of the trigger arms 49, as will be apparent from Fig. 4. As the cross head continues its downward movement, downward pull is exerted upon the trigger arms 49, and as a result the bell crank levers 46 and 47 will be rotated about the axis of pin 39. The rotation of the bell crank levers is transmitted to the pawl supporting arms 37 through the sleeve 38, and the arms 37 are swung outwardly and carry the pawl supporting pin 45 over the center of the toggle, at which moment the pawl kicks over and the doors fly open, causing the shaft 11 and ratchet wheel 35 to spin around at great speed, in clockwise direction with reference to Fig. 4. The downward movement of the cross head 25 up to the moment when the doors fly open is comparatively short, and when the pawl 36 kicks over most of the chain 30 is still slack. The ensuing rapid rotation of shaft 11 and sleeve 31, however, winds up most of the chain 31, and at the moment the doors reach their fully open position there will still be some slack in the chain 31. As the cross head 25 continues its downward movement it takes up this remaining slack, and while this is being done the doors remain fully open for a short time during which the entire load drops out of the wagon box and the vehicle is drawn clear of the pile of material which has been dumped. Depending on the rapidity with which the pressure fluid is forced into the cylinder 23 more or less time is required to take up the remaining slack of the chain 30, and more or less time will be afforded for drawing the vehicle clear of the pile of material which has been dumped. The present tendency in dirt moving operations is towards high speeds; the wagons are drawn by high speed tractors, and as the wagons do not stop or even slow down for dumping, very little time is necessary to clear the dumped load. Consequently, in the present mechanism the chain 30 may almost become tight when it is wound up on the sleeve 20 by the rotation of shaft 11 after the cross head 25 has struck the cross member 51. At any rate, the continued downward movement of the cross head 25 will eventually exert a heavy pull on the chain 30, and under this pull the doors will be closed as has been explained hereinbefore. During the last part of the downward movement of the cross head 25 the bell crank levers 46 and 47 return into their normal position which is shown in Fig. 4, as has been explained hereinbefore, the pawl 36 is moved against the ratchet wheel 25, and during the last part of the closing movement of the doors the pawl rides over the teeth of the ratchet wheel. When the piston in cylinder 23 has reached the lower end of its stroke rotation of shaft 11 stops, and the pawl locks the doors in closed position. It is then necessary to release the pressure of the fluid above the piston 23' in cylinder 23 to permit the springs 27 to return the cross head into its highest position as shown in Fig. 4. In order to release the fluid pressure above piston 23' the operator turns the handle 19 of the valve 72 into the extreme position in which the opening 81 is fully open. The entire fluid above piston 23 is then returned into the reservoir under the action of springs 27, there being practically no pressure set up by the pump because its discharge is then directly connected with the reservoir through the open passage 81. During its return or upward movement the cross head 25 strikes the cross member 51 again, but this time nothing happens except that the cross member 51 is forced out of the way of the cross head against the pressure of spring 52, the cross member 51 sliding back under the cross head 25 as soon as it has been cleared by the latter.

While the piston in the cylinder 23 moves down under fluid pressure, air is forced out of the cylinder from below the piston through a vent 54, and while the piston moves up under the action of springs 27, air is drawn into the cylinder through said vent.

If it is desired to hold the doors open for a longer time than is afforded by the automatic functioning of the mechanism, this may easily be done by rotating the handle 19 from the extreme position in which the passage 81 is fully closed into the other extreme position in which the passage 81 is fully open as soon as the ratchet gear has been tripped by the initial downward movement of the cross head 25, and before the cross head begins to rotate the shaft 11 by pulling on the chain 30. Due to the opening of passage 81 the cross head will return to its highest position, and if it is later desired to close the doors, the passage 81 is again closed and kept closed long enough to force enough fluid into the cylinder 23 to bring the piston 23' down to the lower end of its stroke. The first part of the downward movement of the cross head up to the time when rotation of the shaft 11 is started by pull on the chain 30, may be termed an idling movement of the mechanism, and the part of the downward movement of the cross head which causes rotation of the shaft 11 by pull on the chain 30, may be termed its power movement.

It should be understood that it is not intended to limit the invention to the exact details of construction herein described, for various modifications within the scope of the claims may occur to persons skilled in the art.

What I claim is:

1. In a dump wagon, a door actuating shaft rotatably mounted on the wagon, a frame comprising relatively spaced side members suspended on said shaft and connected by a cross member, a cylinder mounted on said cross member, a piston within said cylinder, a piston rod secured to said piston, a cross head secured to said piston rod, guides for said cross head formed on said side members, coil springs mounted on said cross member and bearing against said cross head, and flexible connecting means between said shaft and cross head, adapted to be wound around said shaft by door opening rotation thereof.
2. A door operating mechanism comprising a horizontally disposed shaft rotatable in door

- opening and door closing directions, means for controlling door opening rotation of said shaft, a reciprocable element mounted for movement in an upward direction towards said shaft and 5 in a downward direction away from said shaft, a flexible element connected at one end with said shaft and at the other end with said reciprocable element, means for selectively actuating said reciprocable element in said upward 10 and downward directions, upward movement of said reciprocable element, after door closing rotation of said shaft and prior to door opening rotation thereof, causing a portion of said flexible element to become slack, and door opening 15 rotation of said shaft, after said slackening upward movement of said reciprocable element, causing said slack portion of said flexible element to be wound around said shaft, and a shelf member secured to said reciprocable element adjacent 20 to the connection of said flexible element therewith providing a support for the slackened portion of said flexible element.
3. In a vehicle, a body having dump doors, a shaft for operating said doors rotatable in door opening and door closing directions, bearings for 25 said shaft mounted on said body, a frame mounted on said shaft for pivotal movement relative to said body about the axis of said shaft, means associated with said frame reacting upon said body to prevent said frame from rotation about the axis of said shaft in the direction of door opening rotation of said shaft, a flexible element connected with said shaft and adapted to be wound upon said shaft by door opening rotation thereof, and a power actuated element 30 mounted on said frame and connected with said flexible element for exerting pull thereon when wound upon said shaft so as to rotate said shaft in door closing direction.
4. In a vehicle, a body having dump doors, a shaft for operating said doors rotatable in door opening and door closing directions, bearings for 35 said shaft mounted on said body, a frame mounted on said shaft for pivotal movement relative to said body about the axis of said shaft, means associated with said frame reacting upon said body to prevent said frame from rotation about the axis of said shaft in the direction of door opening rotation of said shaft, releasable coupling means between said frame and shaft adapted to prevent rotation of said shaft relative 40 to said frame in door opening direction, a flexible element connected with said shaft and adapted to be wound upon said shaft by door opening rotation thereof, and a power actuated element 45 mounted on said frame and connected with said flexible element for exerting pull thereon when wound upon said shaft so as to rotate said shaft in door closing direction.
5. In a vehicle, a body having dump doors, a shaft for operating said doors rotatable in door opening and door closing directions, bearings for 50 said shaft mounted on said body, a frame mounted on said shaft for pivotal movement relative to said body about the axis of said shaft, means associated with said frame reacting upon said body to prevent said frame from rotation about the axis of said shaft in the direction of door opening rotation of said shaft, pawl means 55 on said frame cooperating with ratchet means on said shaft to hold said shaft against door opening rotation while said doors are closed, said pawl means being releasable to permit rotation of said shaft in door opening direction, a flexible element connected with said shaft and 60
- 75

adapted to be wound upon said shaft by door opening rotation thereof, a cylinder supported by said frame, and a piston within said cylinder connected with said flexible element and operable by fluid pressure within said cylinder to exert pull on said flexible element when wound upon said shaft so as to rotate said shaft in door closing direction.

6. In a vehicle, a body having dump doors, a rotatable shaft for operating said doors extending along a wall of said body, a frame having pivotal connection with said shaft, bearing means for said shaft, independent of said frame, secured to said body and adapted to retain said shaft and adjacent portions of said frame transversely spaced from said wall, power actuated mechanism on said frame operatively connected with said shaft to rotate said shaft in one direction, and means associated with said frame reacting upon said body to prevent rotation of said frame about said shaft in a direction opposite to the direction in which said shaft is rotated by said power actuated mechanism.

7. In a vehicle, a body having dump doors, a rotatable shaft for operating said doors extending along a wall of said body, a frame having pivotal connection with said shaft, a pair of axially spaced journal bearings for said shaft, independent of said frame, secured to said body and retaining said shaft and adjacent portions of said frame transversely spaced from said wall, power actuated mechanism on said frame operatively connected with said shaft to rotate said shaft in one direction, and an abutment on said frame reacting upon said body to prevent rotation of said frame about said shaft in a direction opposite to the direction in which said shaft is rotated by said power actuated mechanism.

8. In a vehicle, a body having dump doors, a rotatable shaft for operating said doors and a lineal support, extending along one of the walls of said body, pivotal connecting means between said shaft and support, journal bearings for said shaft secured to said body, an element mounted on said support for reciprocating movement longitudinally thereof and operatively connected with said shaft for rotating said shaft by movement of said element in one direction, and an abutment on said support spaced from said shaft in the direction of said wall and reacting upon said body to prevent rotation of said support about said shaft in a direction opposite to the direction in which said shaft is rotated by said shaft rotating movement of said reciprocable element.

9. In a vehicle, a body having dump doors, a rotatable shaft for operating said doors and a lineal support extending in substantial right angle relation to each other along one of the walls of said body, pivotal connecting means between said shaft and support, journal bearings for said shaft secured to said body, an element mounted on said support for reciprocating movement longitudinally thereof and operatively connected with said shaft for rotating said shaft by movement of said element in one direction, an abutment on said support spaced from said shaft in the longitudinal direction of said support and reacting upon said body to prevent rotation of said support about said shaft in a direction opposite to the direction in which said shaft is rotated by said shaft rotating movement of said reciprocable element.
